UNITED STATES PATENT OFFICE.

HENRY C. MARX, OF PALMER, KANSAS, ASSIGNOR TO THE PHONOHARP COMPANY, OF EAST BOSTON, MASSACHUSETTS, A CORPORATION OF MAINE.

KEYED ZITHER.

1,150,284.

Specification of Letters Patent.

Patented Aug. 17, 1915.

Application filed August 28, 1913, Serial No. 787,156. Renewed February 10, 1915. Serial No. 7,328.

To all whom it may concern:

Be it known that I, HENRY C. MARX, a citizen of the United States, and a resident of Palmer, in the county of Washington and State of Kansas, have invented certain new and useful Improvements in Keyed Zithers, of which the following is a specification.

This invention relates to musical instruments such as citherns.

10 The invention is embodied in means including a series of manually operative strikers whereby the strings of the instrument may be struck and caused to vibrate. The strikers have spring shanks whereby 15 they are capable of vibrating and striking the strings repeatedly to produce the effect of a mandolin. In this respect, the instrument is similar to that set forth in Letters Patent No. 1,044,553, granted to me November 19, 1912.

The present invention embodies improved means for mounting the strikers.

Of the accompanying drawings, Figure 1 represents a vertical section through a 25 stringed musical instrument, showing one form of means for mounting the strikers. Fig. 2 represents a horizontal section through the structure intersected by line 2—2 of Fig. 1. Fig. 3 represents a section 30 similar to Fig. 1 showing a modified form of means for mounting the strikers. Fig. 4 represents an elevation of the supporting means included in Fig. 3. Fig. 5 represents a vertical section in the plane indicated by line 35 5—5 of Fig. 4.

The same reference characters indicate the same parts in all the figures.

The base of the musical instrument is indicated at 10 and the sounding board is indicated at 11. These two elements are affixed to a hitch pin block 12 which is at the front of the instrument, and which is provided with pins 13 by which the strings 14 are anchored.

45 The instrument is provided with a series of strikers 15, each of which is affixed to the free end of a flexible spring shank 16. The shanks are affixed to stiff or non-resilient keys or finger pieces 17 which are adapted to be depressed manually to cause the strikers to impinge against the strings 14.

According to the form illustrated by Figs. 1 and 2, the finger pieces 17 rock upon an edge 18 of a supporting cross bar 19, which serves 50 as a pivot for said finger pieces. This cross

bar or support for the keys extends transversely with relation to the strings 14 and is supported by a bar 20, being detachably affixed to the bar 20 by any suitable means such as screws 21. The bar 20 is affixed to 60 the pin block 12 by screws 22, and is spaced from the pin block by interposed filling pieces such as that indicated at 23, whereby it is held away from the pins 13. The bar 19 is grooved at intervals corresponding to the 65 spacing of the strings 14 to provide recesses 34 for the finger pieces 17.

Two arms 24, one at each end of the series of finger pieces 17, support a rest 25 above the strikers. The function of the rest 25 is 70 to arrest the vibration of the strikers when the finger pieces are released, the strikers being automatically elevated so that they initially bear against the under surface of the rest. In the form shown by Figs. 1 and 75 2, the strikers 17 and the arms 24 are held in their respective recesses in the bar 19 by a strip 26 of elastic material, the upper sides of the elements 17 and 24 being provided with transverse grooves 35 for the reception 80 of the strip 26. The strip 26 is secured between each two adjacent rocking elements by fasteners indicated at 27, the strip 26 being under tension, whereby it is adapted to act as a spring to normally hold the strikers 85 against the rest 25 as shown. The ends of the strip 26 are likewise secured to the bar 19 in order to normally support the rest 25 in the elevated position shown. The elasticity of the strip 26 permits the finger pieces 90 17 to swing downwardly to cause the strikers 15 to impinge against the strings 14. Fig. 1 shows one of the finger pieces depressed, and includes dotted lines indicating the striker and its flexible springy shank at 95 the two extremes of its vibratory movement. In order to cause the desired vibration of the strikers, it is necessary to provide a stop for the finger pieces 17 when they are rocked about their pivot or fulcrum. Such a stop is 100 indicated at 28 in the form of a cross bar or flange extending horizontally from the front bar 20, the flange overhanging all of the finger pieces 17 and the arms 24. When the finger piece is depressed, its forward end 105 strikes the cross bar or flange 28 before the striker 15 engages the string 14, the striker thereafter coacting with the strings by vibration. When the finger piece is released, the spring element 26 raises the striker into 110

engagement with the rest 25 and the opposite end of the key engages the bottom of the recess 34 as shown in Fig. 1. The rest and all of the strikers may be depressed for the purpose of storing or packing the instrument. The strikers may be readily detached from their support by longitudinal movement after first lifting the elastic strip 26 out of the notches formed in the finger pieces. Lateral movement of the strikers is prevented by partitions 29 which separate the finger pieces, and the desired register of the strikers with their respective strings 14 is insured.

15 In the form shown by Figs. 3, 4 and 5, the finger pieces 17 are mounted upon a fulcrum which consists of a wire or rod. The strikers carried thereby are normally raised by springs 31. The finger pieces and the overhanging flange or stop 28 are provided with sockets for the ends of the springs. The flange 28 is provided with depending partitions 32 which register with upstanding partitions 33 formed on the bar 19. The 20 fronting faces of the partitions 32 and 33 are provided with grooves which register with each other and receive the fulcrum wire or rod 30. So far as the pivotal or rocking movement of the finger pieces or keys is concerned, the rod or wire 30 and the edge 18 of the bar or support 19 perform the same function, *i. e.* that of serving as a pivot or fulcrum for the keys. In this sense, the keys in Fig. 1 may be fairly described as 25 pivotally mounted. Further, in Fig. 1, the bar 19, having the edge 18, and the elastic member 26, which holds the keys thereon, may fairly be described as means for pivotally mounting said keys to permit each to be 30 removed separately.

40 Having thus explained the nature of my said invention and described a way of constructing and using the same, although without attempting to set forth all the forms in which it may be made or all the modes of its use, what I claim is:—

1. The combination with a stringed musical instrument, of a support affixed thereto, a stiff key fulcrumed between its ends on said support, a hammer having a spring shank carried by one end of said key and having its head remote from the corresponding string, a stop arranged to be engaged by the other end of said key to limit the operating movement of said key in consequence of which the hammer is caused to vibrate against its corresponding string, and a spring acting upon said key to retract said hammer from said stop and to move the 50 hammer from string-engaging position.

60 2. The combination with a stringed musical instrument having a series of strings, of a series of stiff keys, a support for said keys, said support having partitions for spacing said keys laterally, said keys being

fulcrumed between their ends upon said support, each of said keys having at one end a spring hammer for engaging one of said strings, a fixed member overhanging and arranged to be engaged by the other end of each key to limit the operating movement of the key, and means to retract said hammers from striking position.

3. The combination with a stringed musical instrument, of a series of stiff keys, a support having a series of key-receiving sockets, said keys being detachably arranged in said sockets and adapted to rock upon said support, each of said keys having at one end a spring hammer for striking a musical string, a fixed stop arranged to be engaged by the other end of each key to limit the operating movement of the key, and a strip of elastic material under tension extending across and acting upon said keys to retract said keys, said strip being secured to said support at both sides of each key.

4. The combination with a stringed musical instrument, of a support, a stiff key fulcrumed between its ends on said support, a spring hammer carried by one end of said key for striking a string, a stop above the other end of said key and arranged to be engaged by said other end to limit the operating movement of said key, and a spring member engaged with said support and acting upon said key to retract said hammer from its string when the key is released.

5. The combination with a stringed musical instrument, of a key, a support therefor, said key being fulcrumed between its ends upon said support and adapted to rock thereon, a spring hammer carried by one end of said key for vibrating against a string, a stop arranged to be engaged by said key to limit the operating movement of the key, and an elastic member fastened to said support at both sides of said key and acting upon said key to retract said hammer from striking position, said key having a transverse groove and said strip being arranged in said groove, whereby said key is detachably held against accidental longitudinal movement, but is detachable longitudinally by force.

6. The combination with a stringed musical instrument, of a cross bar, a series of stiff keys loosely resting on said cross bar and adapted to be individually separated therefrom without removing the others, means extending across said keys for holding them on said cross bar, and spring hammers projecting from the free ends of said keys.

7. The combination with a stringed musical instrument, of a cross bar, a series of stiff keys resting upon said cross bar, each key being removable therefrom independent-

ently of the others, spring hammers projecting from the keys at one end thereof, and a hand rest located over the other ends of the keys.

5 8. The combination with a stringed musical instrument, of a series of stiff keys above the strings, means for pivotally mounting said keys to permit each to be removed separately, and spring hammers projecting from said keys.

9. The combination with a stringed musical instrument, of a bar arranged across the strings, a series of spring hammers, a series of stiff keys therefor fulcrumed on 15 said bar and independently removable therefrom, means located above said bar normally to hold said keys against removal from said bar, but movable to allow said keys to be removed separately, and a stop for engaging 20 said keys when they are operated in conse-

quence of which the spring hammers are caused to vibrate against the strings.

10. The combination with a stringed musical instrument, of a bar extending transversely of the strings, a series of stiff keys 25 mounted on said bar between their ends and individually removable independently of the others, a spring hammer projecting from one end of each key, and a second cross bar above the opposite ends of said keys, said 30 bars forming stops to engage the said opposite ends of the keys and limit the oscillation thereof.

In testimony whereof I have affixed my signature, in presence of two witnesses.

HENRY C. MARX.
